REFRIGERATION

Carl A. Otto, Milwaukee, Wis., assignor to Johnson Service Company, Milwaukee, Wis., a corporation of Wisconsin

Application October 2, 1935, Serial No. 43,267

8 Claims. (Cl. 62—8)

This invention relates to refrigeration and particularly to air conditioning under summer conditions by the use of direct expansion coolers forming part of the refrigerating circuit.

5 In pending application Serial No. 35,539, filed August 9, 1935, I describe and claim a device of this character in which an expansion valve of the automatic type is controlled in response to superheat of the refrigerant leaving the evaporator, evaporator pressure, and a temperature condition created by the operation of the evaporator. The temperature condition discussed in that prior application is the differential between an indoor temperature and outdoor temperature.

10 Certain refrigerative circuits are operated at constant suction pressure and in such case the evaporator pressure would disappear as a regulatory factor. The purpose of the present invention is to disclose a modified embodiment of my prior invention in which the evaporator is operated at constant pressure and in which the expansion valve is regulated solely by thermostatic means; that is to say in response to superheat of the refrigerant and in response to a temperature condition created by the operation of the evaporator.

15 Broadly considered it is not essential that the expansion valve used in such a system be indifferent to evaporator pressure for the fact that evaporator pressure is constant makes it possible to introduce a constant balancing force with the result that the valve is properly balanced under operating conditions whether it be indifferent to evaporator pressure or not. However, better results are secured with a valve which actually is indifferent to evaporator pressure, because as a matter of practice it is not practicable to maintain evaporator pressure absolutely constant. For the purposes of this case a valve indifferent 20 to pressure will be regarded as a special instance of a valve which is in effect balanced under constant suction pressure conditions.

The expansion valve herein disclosed includes 25 three thermostatic controls, one of which responds to superheat, one of which responds to an indoor temperature, and another of which responds to an outdoor temperature and exercises a modifying control. Certain of these thermostatic controls may take effect individually and 30 under certain circumstances they may take control collectively, this for the reason that the regulatory effect is permissive in one direction so that under certain conditions one or another control 35 may exert exclusive effect. Means are provided

to adjust the superheat control by means of a loading spring, and means are provided to adjust the relation of the outdoor to the indoor control.

While I have referred to outdoor temperature, 5 it is important to state that this outdoor temperature may be dry bulb temperature, wet bulb temperature, effective temperature (a combination of wet bulb and dry bulb temperatures) or a temperature developed by radiation. Thermo- 10 static elements which will respond to each of these temperatures are well known and their specific construction is not a feature of the present invention.

A simple embodiment of the invention will now 15 be described with reference to the accompanying drawings, in which,—

Fig. 1 is a diagram of the conditioning circuit.
Fig. 2 is an axial section through the expansion valve.

20 Fig. 3 is a conventional representation of a wet bulb thermostatic unit which may be used out of doors.

Fig. 4 is a conventional representation of an effective temperature thermostatic unit which 25 may be used out of doors.

Fig. 5 is a conventional representation of a 30 thermostatic unit responsive to radiant heat.

Referring first to Fig. 2, the body of the expansion valve comprises an annular member 7 having a chamber 8 from which a discharge passage 9 leads. Inlet passage 11 communicates through a radial arm 12 which projects into the chamber 8 and is provided with a downwardly facing valve seat 13 at the center of the chamber 35. This seat controls flow entering through the passage 11 and discharging into the chamber 8. Housing 7 is mounted on a hollow casing 14 which encloses the lever mechanism and serves as a support for the thermostatic motors hereinafter 40 described.

Interposed between the housing 7 and the casing 14 is the marginal flange of a cup-shaped member 15 which serves as a sealing gasket and also as a support for the corrugated metallic 45 bellows 16. The lower end of the bellows is sealed to the member 15 and the upper or movable end is sealed to a head 17 which is in thrust relation with a bifurcated yoke 18. This yoke carries a needle valve 19 which coacts with the valve seat 50 13 and controls the supply of liquid refrigerant to the chamber 8. The upper side of the housing 7 is closed by a cap 21. This seats on the marginal flange of a cup-shaped member 22, which, like the member 15, serves partly as a sealing gasket. 55

- The member 22 supports corrugated metallic bellows 23, whose free or movable end is sealed to a head 24. The head 24 is in thrust relation with the upper end of the yoke 18 already described.
- 5 A coiled compression spring 25 is housed within the cap 21 and reacts in downward thrust upon the head 24. Since the two bellows are of equal diameters the valve 19 is indifferent to pressure within chamber 8. The yoke 18 is preferably 10 rigidly attached to the heads 17 and 24. Acting upward in thrust against the head 17 is a slotted rod 26 which is guided to move vertically in the direction of its axis by means of guideways 27 formed in the casing 14. It responds at times 15 to the individual and at times to the combined effects of several thermostatic motors. The action is modified by an adjustable spring. One thermostatic motor responds to superheat of refrigerant leaving the evaporator and exerts a 20 valve opening effect on rising temperature. Another control is effected by two opposed thermostatic motors, one of which responds to indoor temperature and exercises a valve-opening effect on rising temperature, and the other of 25 which responds to outdoor temperature and exerts a valve closing effect upon rising temperature. The force relation between the last two motors when they act conjointly is subject to modification by a shifting fulcrum.
- 30 The superheat control motor comprises a base 30 which is adjustably mounted on a portion of casing 14 by a nut 28 which is threaded on the casing 14 and swiveled on the base 30. Rotation of the nut therefore shifts the base 30 vertically.
- 35 Mounted on the base 30 is a metallic bellows 29 having a closed head 31 which reacts in downward thrust on a push rod 32. Shell 33 closes the bellows and forms a pressure chamber above and surrounding the same. To this chamber a 40 flexible tube 34 leads from a thermostat which develops increasing pressure on rising temperature. This thermostat might take many forms, but in Fig. 1 it is indicated as a bulb 35 containing an expansible liquid which responds appropriately 45 to rising temperature. In Fig. 1 bulb 35 is shown clamped against the suction line leading from the evaporator.
- A coil compression spring 36 reacts against a flange 37 on rod 32 and is sustained by an adjustable spring seat 38 which is threaded in a portion 50 of the casing 14. By turning the spring seat 38 the stress on the loading spring 36 may be adjusted.
- Pinned to rod 32 is a lever 39 which is fulcrumed 55 at 41 and is in thrust engagement with a pin 42 passing through the slotted portion of rod 26. Lever 39 extends through the slot in the rod, as clearly indicated in the drawings. In this way a one-way thrust connection between the lever 60 39 and the rod 26 is afforded, so that the effect of the superheat control on the expansion valve is permissive in an opening direction but positive in a closing direction.
- Control is normally exercised on the rod 26 by 65 a lever 43 which is fulcrumed at 44 in casing 14 and reacts upward against the pin 45 extending through the slot in the rod 26. The lever extends through the slot in the rod and is in one-way thrust engagement with pin 45, so that the 70 modifying control is permissive in a valve opening and positive in a valve closing direction. The lever 43 is operated primarily by the indoor motor, generally indicated at 46. The outdoor motor, generally indicated at 47, introduces a modifying effect on the action of the indoor motor 46.

The structure of these motors, including the adjusting means, is identical with that already described with reference to parts 28-33 inclusive, and this detailed description need not be repeated. The only structural difference is that 5 motor 46 includes a coil compression spring 48 which resists downward motion of the motor element, as will be apparent from an inspection of the drawings.

The working space of motor 46 is connected by 10 a tube 49 with the indoor thermostat 51. Thermostat 51 may be of any type which will develop a rising fluid pressure in the tube 49, and motor 46, in response to rising temperature. An ordinary thermostatic bulb is indicated in the drawings, but in some cases the use of a pneumatic relay thermostat of the progressive relay type would be preferred particularly if the length of the tube 49 be considerable. Thermostats of this type are well known in the art, and a suitable 20 one is illustrated in Patent to Otto, No. 1,500,260, July 8, 1924.

The bellows of motor 46 reacts downward through a push rod 52 upon lever 43. The outdoor motor 47 is connected by a tube 53 with 25 the outdoor thermostat 54, which may be of any type developing in the tube 53 and motor 47 a pressure which rises in response to rising temperature. In the drawings a thermostatic bulb is indicated but a pneumatic relay thermostat of 30 the type already mentioned would be preferable where the line 53 has considerable length. The particular form of the thermostats to be used to develop the necessary pressure in the thermostatic motors is not a feature of the invention 35 and is largely a matter of choice.

The bellows of motor 47 reacts through a push rod 55 upon a short lever 56 pivoted at 57 in the casing 14. Swiveled in the lever 56 and extending longitudinally thereof is a threaded rod 58. 40 This rod may be turned by a knurled adjusting head 59 and carries threaded upon it a fulcrum block 61 which has a knife edge engaging the lever 43 in one-way thrust and which has a bifurcated lower portion 62 which straddles the 45 lever 56 and holds the block against rotation. By turning the knurled head 59 the fulcrum block 61 is traversed in the direction of the length of the lever 56 and by changing the fulcrum point through which the lever 56 reacts 50 upon motor 43 a change in the force relation between the motors 46 and 47 is effected. In this way response of the expansion valve to concurrent variations of indoor and outdoor temperature may be modified at will.

The outside thermostat 54 shown in Fig. 1 55 may be assumed to be a dry bulb instrument. It can be converted into a wet bulb instrument by giving it a wet envelope 63, as indicated in Fig. 3, or into an effective temperature thermometer 60 by giving it a partial wet envelope 64, as indicated in Fig. 4. It can be caused to respond to radiant heat by enclosing it in a black copper hollow sphere 65, as indicated in Fig. 5, and the interchangeable use of these different types of 65 thermostatic units is contemplated.

In Fig. 1 the expansion valve of the type described is shown inserted in an air conditioning system of the direct expansion constant suction pressure type. In this figure 66 is the housing 70 of the conditioner and 67 represents the conditioned room or space enclosed as indicated. A recirculation duct 68 leads recirculated air to the intake of the conditioner, while the louvers 69, which may be manually or otherwise adjusted, 75

admit fresh air. The air entering through the recirculation duct and the louvers mixes and passes in contact with the evaporator 71 from which it passes to the total volume fan 72 and thence to the conditioned space 61. Any preferred air circuit may be used and the use of washing sprays is possible but not a feature of the invention and consequently not illustrated. The same applies to preheaters, reheaters and other equipment familiar in the art and not entering into the claimed invention.

Leading from the evaporator 71 is the suction line 73 to which the thermostatic bulb 35 is attached. This line leads through a suction pressure regulating valve 74 and a suction pressure switch 75 to a compressor 76 driven by a motor 77. The suction pressure regulating valve 74 is merely a diaphragm operated pressure reducing valve which maintains the pressure in the evaporator 71 constant within relatively close limits. Valves of this type are too well known to require detailed description.

The suction pressure switch 75 is used to prevent the compressor 76 from operating at too low suction pressure and its function is to operate through a magnetic starter 78 to reduce the speed of the motor 77 and the compressor 76 at times when the suction pressure regulating valve 74 is so nearly closed that the compressor 30 would operate at an unduly low suction pressure if maintained at full speed. This scheme of regulating suction pressure by a suction pressure regulating valve while the speed of the compressor is varied to prevent inefficient operation is one of various systems used in the refrigerating art to maintain a substantially constant suction pressure on an evaporator. No novelty is here claimed for this particular mechanism and various equivalents may be substituted.

40 The compressor 76 discharges through the high pressure line 79 to the condenser, diagrammatically indicated at 81. Refrigerant liquefied in the condenser flows to the receiver 82 and thence through the liquid line 83 to the inlet connection 11 of the expansion valve. Refrigerant is delivered through the connection 9 of the expansion valve and pipe 84 connected thereto to the evaporator 71.

Since the suction pressure is substantially constant, it is unnecessary and in fact impracticable to cause the expansion valve to respond to suction pressure. Thus it is possible and desirable to avail of the free-operating characteristics of a balanced valve, particularly a valve indifferent to pressure.

The operation of the device can now be outlined. The existence of superheat at the bulb 35 will develop pressure in motor 30 and permit the valve 19 to open wide. It will open wide as the system is started up. After the system has been in operation the thermostat 51 will take control through motor 46 and this control may or may not be modified by thermostat 54 through motor 47, depending on the differential between the control point of thermostat 51 and outside temperature.

70 The purpose of the differential control is to limit the depression of indoor temperature below outdoor temperature. The limit so placed may be varied by adjusting fulcrum 61.

During normal operation the thermostat 35 does not control, but it may assume control if the thermostat 51 makes an abnormal demand for refrigeration, as it does in starting up the system, and as it may do under certain abnormal

conditions in the refrigerated space producing an excessive heat load. The thermostat 35 may temporarily assume control if the thermostat 54 functions to produce a marked change in the controlling action of thermostat 51.

Thus the controls by superheat and by space temperature are alternative in effect, and the selection between the two is automatically made on the basis of selecting that control which indicates the lower demand for refrigerant. Thus 10 the coil is never overloaded with refrigerant and all danger of wrecking the compressor is avoided.

While a particular embodiment of the invention has been described in detail, the invention is broader than any particular means for carrying it out. Hence the disclosure is intended to be illustrative rather than limiting, the scope of the invention being defined solely by the claims.

What is claimed is,—

1. The method of controlling the refrigerative effect of a space-cooling evaporator, which comprises, withdrawing refrigerant vapor from the evaporator and varying the rate of withdrawal to maintain a constant suction pressure; admitting liquid refrigerant to the evaporator and controlling the rate of admission in response alternatively to the temperature of discharging refrigerant vapor and to the space temperature created by the evaporator; and selecting between such alternative temperature controls on the basis of the lower demand for refrigerant.

2. The method of controlling the refrigerative effect of a space-cooling evaporator, which comprises, withdrawing refrigerant vapor from the evaporator and varying the rate of withdrawal 35 to maintain a constant suction pressure; admitting liquid refrigerant to the evaporator and controlling the rate of admission in response alternatively to the temperature of discharging refrigerant vapor and to the space temperature 40 created by the evaporator; selecting between such alternative temperature controls on the basis of the lower demand for refrigerant; and modifying the second-named control in accordance with an external temperature which affects heat leak- 45 age to said cooled space.

3. In a refrigerating system, the combination of a source of liquid refrigerant; a space cooling evaporator; means for maintaining a substantially constant suction pressure in said evaporator; 50 an expansion valve controlling the supply of liquid refrigerant to said evaporator; and at least two thermostatic controlling means for said valve, one of which responds to the temperature of refrigerant leaving said evaporator and another to the space temperature created by said evaporator, said controlling means being so arranged that either may move said valve in a closing direction unaffected by the other.

4. In a refrigerating system, the combination 60 of a source of liquid refrigerant; a space cooling evaporator; means for maintaining a substantially constant suction pressure in said evaporator; an expansion valve substantially indifferent to pressure in the evaporator and controlling 65 the supply of liquid refrigerant to said evaporator; and at least two thermostatic controlling means for said valve, one of which responds to the temperature of refrigerant leaving said evaporator and another to the space temperature 70 created by said evaporator, said controlling means being so arranged that either may move said valve in a closing direction unaffected by the other.

5. In a refrigerating system, the combination 75

of a source of liquid refrigerant; a space cooling evaporator; means for maintaining a substantially constant suction pressure in said evaporator; an expansion valve controlling the supply 5 of liquid refrigerant to said evaporator; and three thermostatic controlling means for said valve, one of which responds to the temperature of refrigerant leaving the evaporator, another to the space temperature created by the operation 10 of said evaporator, and the third to a temperature external to the space and affecting heat leakage thereto, the parts being so arranged that the first controlling means may move said valve in a closing direction unaffected by the second 15 and third, and the second and third by their combined effect may move the valve in a closing direction unaffected by the first.

6. In a refrigerating system, the combination of a source of liquid refrigerant; a space cooling evaporator; means for maintaining a substantially constant suction pressure in said evaporator; an expansion valve substantially indifferent to pressure in the evaporator and controlling the supply of liquid refrigerant to said 20 evaporator; and three thermostatic controlling means for said valve, one of which responds to the temperature of refrigerant leaving the evaporator, another to the space temperature created by the operation of said evaporator, and the third to a temperature external to the space and affecting heat leakage thereto, the parts being so arranged that the first controlling means may move said valve in a closing direction unaffected by the second and third, and the second and 25 third by their combined effect may move the valve in a closing direction unaffected by the first.

7. In a refrigerating system, the combination of an evaporator; an expansion valve for supplying refrigerant to said evaporator, said valve being substantially indifferent to evaporator pressure; means biasing said valve in an open- 30

ing direction; means for maintaining a substantially constant suction pressure in said evaporator; thermostatic means subject to the discharge temperature of the evaporator and exercising a permissive control on said expansion valve in an 5 opening direction upon rise of discharge temperature; and differential thermostatic means comprising two thermostatic devices, one subject to the temperature of the space refrigerated by the evaporator and the other subject to an 10 outdoor temperature, in operation the two thermostats being opposed to each other, the indoor thermostat functioning in a valve opening direction on rising temperature, said differential thermostat exercising a permissive control on said 15 valve in an opening direction and a positive control in a closing direction.

8. In a refrigerating system, the combination of an evaporator; an expansion valve for supplying refrigerant to said evaporator, said valve 20 being substantially indifferent to evaporator pressure; means biasing said valve in an opening direction; means for maintaining a substantially constant suction pressure in said evaporator; thermostatic means subject to the discharge 25 temperature of the evaporator and exercising a permissive control on said expansion valve in an opening direction upon rise of discharge temperature; differential thermostatic means comprising two thermostatic devices, one subject to the temperature of the space refrigerated by the evaporator and the other subject to an outdoor 30 temperature, in operation the two thermostats being opposed to each other, the indoor thermostat functioning in a valve opening direction on rising temperature, said differential thermostat 35 exercising a permissive control on said valve in an opening direction and a positive control in a closing direction; and adjustable means for modifying the leverage relation between the indoor and outdoor thermostatic means.

CARL A. OTTO.
